(57) **CLAIM**

The ornamental design for pajamas with inseam zipper, as shown and described.

DESCRIPTION

FIG. 1 is a front elevation view of pajamas with inseam zipper showing my new design;

FIG. 2 is a rear elevation view thereof;

FIG. 3 is a right side elevation view thereof, the left side elevation view being a mirror image of FIG. 3;

FIG. 4 is a top plan view thereof;

FIG. 5 is a bottom plan view thereof;

FIG. 6 is a front elevation view thereof showing an alternate position with the zipper unzipped; and,

FIG. 7 is a rear elevation view of FIG. 6.

The dash-dash broken lines illustrate portions of the pajamas with inseam zipper that form no part of the claimed design. The dot-dash broken lines represent a boundary of the claimed design.

The stippling shown within the drawing disclosure represents shading that forms part of the claimed design.
